TOY FIGURE

John M. Auzin, Whitman, Mass.

Application January 31, 1951, Serial No. 14,045

Term of patent 14 years

(Cl. D34—4)

To all whom it may concern:

Be it known that I, John M. Auzin, a citizen of the United States, residing at Whitman, State of Massachusetts, have invented a new, original, and ornamental Design for a Toy Figure, of which the following is a specification, reference being had to the accompanying drawing, forming a part hereof.

Fig. 1 is a front view of a toy figure, showing my new design; and

Fig. 2 is a side view thereof.

I claim:

The ornamental design for a toy figure, as shown.

JOHN M. AUZIN.
